DESIGN FOR A PLATE OR SIMILAR ARTICLE

John Edward Goodwin, Penrhyn Bay, Llandudno, North Wales, assignor to Josiah Wedgwood & Sons, Inc. of America, New York, N. Y., a corporation of New York

Application April 24, 1935, Serial No. 56,541

Term of patent 7 years

To all whom it may concern:

Be it known that I, John Edward Goodwin, a subject of Great Britain, residing at Etruria, St. David's Road, Penrhyn Bay, Llandudno, N. Wales, British Isles, have invented a new, original, and ornamental Design for a Plate or Similar Article, of which the following is a specification, reference being had to the accompanying drawing, forming part thereof.

The drawing is a plan view of a plate embodying my new design.

I claim:

The ornamental design for a plate or similar article as shown.

In testimony whereof I have signed my name to this specification.

J. E. GOODWIN.
